UNITED STATES PATENT OFFICE.

ANDREW A. KUCHER, OF CHESTER, PENNSYLVANIA, ASSIGNOR TO WESTINGHOUSE ELECTRIC & MANUFACTURING COMPANY, A CORPORATION OF PENNSYLVANIA.

REFRIGERATOR.

Application filed June 4, 1923. Serial No. 643,364.

My invention relates to refrigerating machines, particularly to small capacity machines of the compression type which are suitable for household use. It has for an object to provide a novel method and means for lubricating the mechanism which shall be effective during long periods of service without attention.

It has for another object to provide means for lubricating the mechanism which shall be adapted to employ a working fluid having as constituents a refrigerant and a lubricant admixing therewith to form a homogeneous fluid and separable only by vaporization.

It has for another object the utilization of the heat generated by the compression mechanism to separate by vaporization the refrigerant component of the working fluid, and for conveying the remainder of the working fluid to the working parts of the machine.

It has for a still further object to provide an original and novel means for conveying lubricant to the working parts of the compressor and the motor, and for collecting the lubricant discharged therefrom by entraining the same in the refrigerant vapor passing from the evaporator to the compressor.

These and other objects, which will be made apparent throughout the further description of the invention, may be attained by the employment of the apparatus hereinafter described and illustrated in the accompanying drawing in which Fig. 1 is a view in section illustrating the condensing chamber and compression mechanism of a refrigerator in which my invention may be practiced; Fig. 2 is a plan view of the compressor taken on the line II-II of Fig. 1 and Fig. 3 is a view in perspective of the upper portion of the motor shaft with the compressor shaft removed.

Compression refrigerators nominally comprise a chamber in which a working fluid is evaporated at a relatively low pressure and temperature, a chamber in which the vapors are condensed at a higher pressure and temperature, a compression mechanism for translating the vapors from the evaporation chamber to the condensing chamber, and a valved conduit for returning the condensed fluid at a reduced pressure into the evaporation chamber.

The cycle is continuous during any period of operation, heat being absorbed from the

medium surrounding the evaporation chamber to secure the desired refrigerating effect, which heat is removed from the apparatus by bringing an outside medium into heat-exchanging relation with the conduits of the condensing chamber. Apparatus of this character generally operates intermittently; for example, a period of operation of from one to one and one-fourth hours being followed by a period of inactivity of from one and one-half to two hours, the length of the periods depending upon the duty imposed upon the refrigerator and upon the setting of the automatic devices which control the starting and stopping of the compression mechanism. In general, the compression mechanism is tightly encased to prevent escape of the working fluid and, for this reason, some means for the lubrication thereof must be provided which will operate without attention continuously and reliably for long periods of time, as for example, for one or more years. It is to this problem of effectively lubricating enclosed compression mechanisms associated with refrigerators of the type above indicated, that the present invention relates.

It has heretofore been proposed to employ in compression refrigerators a lubricant which is immiscible with the refrigerant. Many liquids possessing to a greater or less extent this property have been used, generally with incomplete success, since no combination of refrigerant and lubricant has been found in which the liquids do not mingle to some extent when brought together under the conditions of agitation obtaining in a compression refrigerator. Mechanical separators of various types have been employed in connection with machines of this character to facilitate the segregation of the lubricant and the refrigerant. This expedient has improved the operation but has not resulted in accomplishing sufficiently complete segregation of the fluids to enable compression refrigerators utilizing a compound working fluid of this character to operate for long periods without the replacing of the lubricant.

In my machine, I employ a working fluid consisting of a refrigerant and a lubricant which readily mix one with the other to form a homogeneous or liquid solution, and which I have disclosed in my Patent No. 1,645,198,

issued Oct. 11, 1927, and entitled "Working fluid for refrigeration." This working fluid is of such character that its constituents are mechanically inseparable. Separation may, however, take place by the vaporization of one of the constituents due to sufficient temperature or pressure changes.

By applying the heat generated by the compression mechanism to the liquid working fluid, a change of temperature is produced sufficient to vaporize off the refrigerant but not the lubricant. The refrigerant having been vaporized off, I convey the remainder of the liquid working fluid, which is substantially lubricant and which for reasons of brevity I may hereafter designate as "lubricant", to the working parts of the machine. After being discharged therefrom, the lubricant is conveyed to the inlet port of the compressor, wherein it once more mingles with the refrigerant and at the same time serves to lubricate in passing through, the relatively moving parts of the compressor.

In my apparatus, I employ a hollow motor shaft, utilizing the bore of the shaft to convey the lubricant discharged by one of the bearings of the motor to the remaining bearing. In addition thereto, I employ a novel and improved arrangement of guards and baffles for confining the lubricant and for preventing leakage upon the current bearing portions of the motor. I have found that by the use of an arrangement of lubricant conveying means as herein disclosed, adequate lubrication of the apparatus over long and extended periods of time is ensured, without in any way endangering the motor by the leakage of lubricant.

Referring to the drawings for a detailed description of my invention, I show the condensing chamber of a refrigerator of the type disclosed in a copending application of mine, serially numbered 509,672, filed October 22, 1921, and entitled "Refrigeration machine", and in which my novel method of operation may be carried out. It is to be understood that this invention may be practiced in other types of compression machines, and that the apparatus illustrated and herein described is employed by way of example and as an aid in presenting a clear exposition of my invention. As illustrated, 10 designates a condensing chamber. A compressor 11 driven by a suitable motor 12 is disposed within the chamber. The condensing chamber 10 comprises a bell or dome 13 secured to a base plate 14 as by tap bolts 15 and a flange ring 16. Supported upon the base plate 14 is an inverted cup-shaped casting 17 forming a housing for the motor, and superimposed thereon is a receptacle 18 which houses the compressor 11 and serves as a collection chamber for the liquid working fluid discharged thereby. Suspended from the base plate 14 is a removable cup-shaped casting 19 for permit-

ting a renewal of the commutator brushes which are associated with the motor.

A hollow shaft 21 is associated with the motor and is rotatably secured to a compressor shaft 22 by suitable keys 23, shown in Fig. 70. These keys are fixed in the motor shaft 21, and slidably engage the compressor shaft 22 in an axial direction, thereby permitting freedom of axial movement between the shafts and greatly facilitating assembly of the compressor and the motor. The shaft mechanism is supported by a lower bearing 24 provided in the casting 19, an intermediate bearing 25 provided in the upper portion of the casting 17, and an upper bearing 26 provided in the compressor. The compressor may be of any well-known type. As shown, it comprises a housing 27 and an end cover 28, which includes the upper bearing 26. The housing 27 is provided with a cylindrical bore into which opens an inlet port 29 and an outlet port 30. The inner bored surface of the housing has arcuate grooves 31 and 32 which communicate with the ports 29 and 30 respectively. A rotor 33 is mounted upon the shaft 22, the rotor and shaft being eccentrically disposed with respect to the bore of the housing 27. Radial slots 34 provided in the rotor 33 are adapted to receive slidable vanes 35. The radial slots 34 are so spaced 85 from the shaft 22 as to provide sufficient continuous surface upon the rotor for the formation of a liquid seal by the lubricant passing radially outward between the cover 28 and the upper end face of the rotor 33. The vanes 35 are provided with tip pieces 36 which slidably engage the inner bore of the housing 27 and are free to assume any degree of angularity required by the contour of said bore. The vanes 35 are held radially outward 90 and the tip pieces 36 are in turn held against the bore of the housing 27 by rods 37 and springs 38. The rods 37 are arranged in holes provided in the rotor and shaft, and the springs 38 surround the respective rods and 95 exert outward pressure against the vanes.

The discharge port 30 of the compressor communicates with a conduit 41 having an open end 42 and supporting a baffle 43 for separating the mixed liquid working fluid and refrigerant vapor discharged from the compressor. The receptacle 18 communicates with the condensing chamber through an outlet 44 provided in the upper portion thereof for the passage of refrigerant vapors, and through an opening 45, whereby an excessive rise in the level of the liquid working fluid within the receptacle is prevented. Condensing coils 46 are arranged in the upper part of the dome 13 and are provided with an inlet connection 47 and an outlet connection (not shown) which pass without the chamber. The condensed fluid is conveyed to the evaporator by a conduit 47 and the flow is controlled by a reducing valve 48. The re- 100

ducing valve 48 is actuated by a float 49, whereby a constant body of liquid is maintained in the condensing chamber. Refrigerant vapor is returned from the evaporator 5 through a passage 51 arranged concentrically without the discharge conduit 47 and communicating with the suction port 29 of the compressor. An electric cable 52 for furnishing current to the motor passes through 10 a gas-tight plug 53 located in the base plate 14.

Lubricant is supplied to the upper shaft bearing 26 by means of an inverted bent tube 54 having an open inlet 55 and having its discharge end communicating through a reducer 56, with a cylindrical passage 57 arranged co-axially with the shaft. Lubricant then passes by means of a groove 58 into the wearing surfaces of the upper bearing 26 and is 20 discharged at the lower end thereof upon the rotor of the compressor. After passing through the various clearances between the working parts of the compressor, the lubricant moves downwardly through a groove 59 to lubricate the bearing 25. It then seeps downwardly between the shaft and the casing and is trapped by a circular groove 61 provided in the compressor shaft 22. The circular groove 61 communicates through a 30 radially disposed opening 62 and a hollow portion 63 of the compressor shaft with a conduit 64 which extends downwardly into the hollow motor shaft 21.

In order to prevent lubricant, which may 35 seep past the circular groove 61, from falling upon the armature windings of the motor, I provide an oil catcher 65 which is soldered or welded to a jacket 66 which in turn is soldered or welded to the motor shaft 21. Any lubricant which may seep past the trapping means or circular groove 61 falls upon the upper 40 end face of the motor shaft 21 and is thrown radially outward by centrifugal force into the oil catcher 65. The lubricant is drained 45 from the oil catcher 65 by means of an opening 67 and a longitudinal groove 68 which communicates with the bore of the motor shaft 21.

The lubricant is discharged at the lower 50 end of the motor shaft into a circular recess 71 provided in the cup-shaped casting 19. The circular recess 71 communicates with an annular opening 72 formed by the ball retainer rings 73 and 74 of the bearing 24. It 55 further communicates through an opening 75 with an annular passage 76, which in turn is drained by means of a conduit 77. The conduit 77 is connected through a union connection 78 to the suction pipe 79 through 60 which the compressor draws refrigerant vapors from the evaporators. The lower surface of the annular passage 76 is disposed a slight distance below the center line of the balls 85, and a level of lubricant corresponding thereto is consequently maintained about

the bearing. This construction provided ample lubrication for the bearing and at the same time insures against an excess accumulation of lubricant in the lower portion of the motor housing.

In order to further guard against lubricant being carried upwardly by the shaft and coming in contact with the current bearing portions of the motor, I interpose a series of baffles between the motor and the bearing 24. I have found from experiment, that upon a stoppage of the apparatus, there is an equalization of pressure between the condensing chamber and the motor chamber and that the gas flowing back through the conduit 77 sprays the lubricant, which may be contained in the conduit 77, back into the motor chamber. I therefore provide a check valve 80 which is disposed in the conduit and a baffle 81 which is snugly fitted in the bore of 85 the casting 19. This baffle extends over the inlet end of the conduit 77, and any lubricant which may leak past the check valve and be sprayed therefrom is impinged upon it. I also provide a baffle 82, which is rotatable 90 with the motor shaft, and a sleeve 83. This sleeve transmits the weight carried by the shaft mechanism to the ball retainer 74 and also holds the baffle 82 rigidly against a suitable shoulder provided on the motor shaft. 95

Any lubricant which may creep upwardly on the sleeve 83 is carried on to the baffle 82 and is thrown tangentially therefrom by the action of centrifugal force. Communication between the motor and the bearing 24 is still 100 further restricted by a third baffle 84 which is fixed in the casting 19, and through which the motor shaft extends, making a close clearance therewith.

The operation of the apparatus thus described is as follows: The condensing chamber 10 and the receptacle 18 disposed therein are filled to a level such as indicated on the drawing with a suitable working fluid. The working fluid generally employed in my apparatus is a combination of a refrigerant and a lubricant which readily mix one with the other to form a homogeneous liquid or physical solution. Upon starting the motor 105 12, the compressor 11 discharges through the port 30 and conduit 41 a commingled liquid working fluid and vapor which impinge upon the baffle 43. The liquid working fluid and the vapor are substantially separated thereby, the liquid falling to the lower portion of the 110 receptacle 18 and the vapor passing out through the opening 44 into the condensing chamber. The liquid working fluid within the receptacle, being subject to the heat of the compressor 11, refrigerant contained 115 therein is vaporized off, leaving a body of liquid containing a high percentage of lubricant.

The hot refrigerant vapors after passing 120 through the opening 44, come into contact 125 130

with the coils 46 and are condensed by the cooling action thereof. The liquid refrigerant falls to the lower portion of the condensing chamber, and, upon sufficient rise of 5 liquid level therein, the float 49 will act to open the reducing valve 48 to permit a flow of liquid refrigerant through the conduit 47 to the evaporators. Within the evaporators (not shown), the refrigerant liquid is evaporated by the absorption of heat from the refrigerator box, and the refrigerant vapors return through the conduit 79 and passage 51 to the inlet port 29 of the compressor 11. Lubrication of the working parts of the 15 compression mechanism is accomplished as follows: The liquid working fluid contained in the receptacle 18, which has been subjected to the heat of the compressor and therefore contains a high percentage of lubricant, is 20 conveyed by means of the conduit 54 and the difference in pressures prevailing between the motor chamber and the condensing chamber to the cylindrical opening 57, provided in the upper portion of the compressor. The lubricant feeds downwardly through the groove 58, is carried into the wearing surfaces of 25 the bearing 26, and is deposited at the lower end thereof upon the end face of the rotor 33. Because of the action of centrifugal 30 force, the lubricant is then carried radially outward between the end cover 28 and the end face of the rotor 33 until a portion thereof drains downwardly through the clearances provided between the slots 34 and the vanes 35. The slots 34 are so spaced from the shaft, 35 however, that prior to a portion of the lubricant being removed from the end face of the rotor, a completely circular liquid seal has been formed between the rotor and the end cover 28, whereby the efficiency of the compression mechanism is very materially improved. The lubricant which is not drained 40 downwardly through the clearances between the slots 34 and vanes 35, is carried outwardly and down over the circular face of the rotor 33. A portion of this lubricant is entrained in the refrigerant vapors passing through the compressor, while the remaining portion, together with the lubricant from the slots 45 34, is deposited upon the upper surface of the motor housing 17. The lubricant deposited thereon forms a film of liquid between the rotor 33 and the upper surface of the motor housing 17, and a portion of this lubricant is 50 in turn conveyed by means of the difference in pressures prevailing within the receptacle 18 and the motor housing 17 into the groove 59 and thence to the wearing surfaces of the intermediate bearing 25. This lubricant then 55 seeps downwardly between the compressor shaft and the housing, and a considerable portion is trapped within the circular groove 61, and, by means of the relatively low pressure prevailing within the motor housing 60 65 17, the opening 62 and the hollow portion

63 of the compressor shaft, is conveyed into the conduit 64 and thence to the bore of the motor shaft 21.

A small quantity of lubricant may seep past the circular groove 61 and be discharged 70 from the lower end of the bearing. This lubricant will be deposited upon the upper end face of the motor shaft 21, whereupon it will be thrown outward, by the action of centrifugal force, into the lubricant catcher 65. 75 It is retained in the lubricant catcher, by the action of centrifugal force, until such time as there is a stoppage of the apparatus, whereupon the lubricant drains by gravity, through the opening 67 and groove 68 to the 80 bore of the motor shaft 21. By the employment of such apparatus for catching lubricant discharged from a bearing located directly above a motor, the possibility of leakage of the lubricant upon the current bearing 85 portions thereof is very remote. I have found from experiment, that my apparatus may be operated for long and extended periods of time, without injury whatsoever to the windings of the motor because of lubrication troubles.

Lubricant discharged from the lower end of the motor shaft 21 passes to the circular recess 71 and to the bearing 24. The lubricant is withdrawn from the bearing through the 95 opening 75 to the annular passage 76, and thence to the conduits 77 and 79 to the passage 51 which communicates with the inlet port of the compressor. A body of lubricant having a level slightly below the center line 100 of the balls 85 is maintained about the bearing. This relatively low level of lubricant is sufficient to insure adequate lubrication of the bearing, and at the same time reduces to a minimum the possibility of excess liquid being carried upwardly by the shaft towards 105 the motor.

Upon the lubricant being drawn into the compressor, it may again be discharged into the receptacle 18 and the cycle of operation 110 repeated. Should the level of the liquid working fluid within the receptacle rise at any time above the opening 45, the excess liquid working fluid, containing a high percentage of lubricant, overflows into the condensing chamber and commingles with the liquid working fluid therein. Upon an opening of the reducing valve 48, it is conveyed to the evaporators (not shown). The method of circulating the liquid working fluid, having 115 contained therein a quantity of lubricant, through the evaporators and back to the compressor, is disclosed in my Patent No. 1,656,918 issued January 24, 1928, and entitled "Refrigerator".

While I have shown my invention in but one form, it will be obvious to those skilled in the art that it is not so limited, but is susceptible of various other changes and modifications without departing from the spirit there- 125 130

of, and I desire, therefore, that only such limitations shall be placed thereupon as are imposed by the prior art or as are specifically set forth in the appended claims.

5. What I claim is:

1. In a refrigerating apparatus, the combination of a body of liquid working fluid composed of an intimate mixture of a refrigerant and a lubricant, a closed condensing chamber, 10 a compressor for discharging refrigerant vapor and entrained liquid working fluid, said compressor being disposed within the condensing chamber, means provided within the condensing chamber for subjecting the liquid 15 working fluid discharged by the compressor to heat for vaporizing off its refrigerant component, and means for employing the liquid working fluid thus treated for lubricating parts of the apparatus.
2. In a refrigerating apparatus, the combination of a body of liquid working fluid composed of a refrigerant and a lubricant which together form a homogeneous mixture, a closed condensing chamber, a compressor for 25 discharging refrigerant vapor and entrained liquid working fluid, said compressor being disposed within the condensing chamber, means provided within the condensing chamber for collecting the liquid working fluid 30 discharged by the compressor and for subjecting it to the heat generated by said compressor for vaporizing off its refrigerant component, and means for employing the remaining liquid for lubricating portions of the apparatus.
3. In a refrigerating apparatus in which a working fluid composed of an intimate mixture of a refrigerant and lubricant is employed, the combination of a condensing chamber, a motor and compressor within said condensing chamber, means within the condensing chamber for collecting the liquid portion 40 of the working fluid discharged by the compressor and for subjecting said liquid working fluid to the heat of the motor and the compressor for vaporizing off the refrigerant from the liquid portion of the discharged working fluid, and means for employing the liquid working fluid thus treated for lubricating 45 the motor and the compressor.
4. In combination, means for circulating a refrigerant medium in a closed cycle, means permitting the circulation of lubricating medium with the refrigerant medium 55 during the entire compression portion of the refrigerant medium circulating cycle, means for substantially separating the lubricating medium and refrigerating medium by the application of heat at a predetermined point in 60 the cycle, means for utilizing portions of the separated lubricant medium to lubricate the refrigerant medium circulating means, and means for entraining these portions in the expanded refrigerant medium passing to the 65 refrigerant medium circulating means.
5. In a refrigerating apparatus in which a working fluid composed of an intimate mixture of a refrigerant and lubricant is employed, the combination of a condensing chamber, means provided in the condensing 70 chamber for maintaining a substantially constant level of liquid working fluid therein, a receptacle for liquid working fluid within the condensing chamber, means for subjecting the liquid working fluid within the receptacle 75 to heat for vaporizing off the refrigerant, and means for limiting the maximum level of the liquid working fluid thus treated, the said maximum level in the receptacle being higher than the level of the liquid working fluid in 80 the condensing chamber.
6. In a refrigerating apparatus, the combination of a body of working fluid composed of an intimate mixture of a refrigerant and a lubricant which together form a physical 85 solution, a closed condensing chamber, a receptacle for liquid working fluid, a compressor disposed in the liquid working fluid contained in the receptacle and having its discharge port communicating with the receptacle and with the condensing chamber, whereby the discharge pressure of the compressor prevails within the receptacle and in 90 the condensing chamber, and conduit means subject to the pressure prevailing within the 95 receptacle for conveying the liquid surrounding the compressor to the working parts of the apparatus.
7. In a refrigerating apparatus, the combination of a body of liquid working fluid 100 composed of an intimate mixture of a refrigerant and a lubricant, a condensing chamber, a compressor for discharging refrigerant vapor and entrained liquid working fluid, a baffle disposed in the path of the combined 105 liquid and vapor discharged by the compressor, whereby the vapor and the liquid are separated, a receptacle for collecting the separated liquid working fluid, said receptacle being disposed in heat exchanging relation 110 with the compressor, whereby the heat of the compressor is utilized to maintain a portion of the liquid working fluid predominantly lubricant, and means for employing said portion to lubricate parts of the apparatus, and 115 means for returning said portion to the intake port of the compressor.
8. In a refrigerating apparatus in which a working fluid composed of an intimate mixture of a refrigerant and a lubricant is employed, a condensing chamber, a receptacle for liquid working fluid within the condensing chamber, a compressor disposed in the liquid working fluid whereby the heat of the compressor may be employed to vaporize 120 off refrigerant from the liquid working fluid, a motor chamber, a motor disposed therein, a shaft structure having a hollow portion for transmitting torque from the motor to the compressor, a bearing for said shaft provided 125

in the compressor, a second bearing for the shaft interposed between the motor and the compressor, a third bearing for supporting the shaft provided in the motor chamber, 5 means for conveying the liquid working fluid, which has been subjected to the heat of the compressor, as lubricant to the first bearing, means for utilizing the lubricant discharged from said bearing to form a liquid seal between the rotor and the casing of the compressor and to lubricate the working parts thereof, means for conveying a quantity of the lubricant passing through the compressor to the second bearing, means for trapping 10 said lubricant, upon passing through the bearing, and for conveying it to the hollow portion of the shaft structure, means for catching lubricant which may seep past the trapping means, means for discharging the 15 caught lubricant to the hollow portion of the shaft structure during non-operation of the apparatus, means for conveying the lubricant from the hollow portion of the shaft to the third bearing, and pumping means for removing the lubricant from the last-mentioned 20 bearing.

9. In a refrigerating apparatus, in which a liquid is evaporated in one chamber, the vapor is pumped into another chamber and 30 condensed therein at a higher pressure and thence returned to the first chamber at a reduced pressure, the combination of a compressor, a motor for driving the compressor, means for utilizing at least a portion 35 of the heat generated by the motor for vaporizing off the refrigerant component of the liquid working fluid, and means for utilizing the residuum as a lubricating fluid.

10. In a refrigerating apparatus in which a liquid is evaporated in one chamber, the vapor is pumped into another chamber and condensed therein at a higher pressure and thence returned to the first chamber at a reduced pressure, the combination of a 40 compressor, a motor for driving the compressor, means for utilizing at least a portion of the heat generated by both the motor and the compressor for vaporizing off the refrigerant component of a portion of the 45 liquid working fluid, and means for utilizing the residuum as a lubricating fluid.

11. In a refrigerating apparatus in which a liquid is evaporated in one chamber, the vapor is pumped into another chamber and 50 condensed therein at a higher pressure and thence returned to the first chamber at a reduced pressure, the combination of a body of liquid working fluid composed of an intimate mixture of a refrigerant and a lubricant which together form a physical solution, a 55 compressor for discharging refrigerant vapor and entrained liquid working fluid, a driving motor therefor, means for separating the liquid working fluid from the refrigerant vapor discharged by the compressor 60

sor, means for utilizing the heat generated by the compressor to vaporize off the refrigerant component of the separated liquid, and means for utilizing the residuum for lubricating the compressor and motor. 70

12. In a refrigerating apparatus in which a liquid is evaporated in one chamber, the vapor is pumped into another chamber and condensed therein at a higher pressure and thence returned to the first chamber at a reduced pressure, the combination of a body of liquid working fluid composed of an intimate mixture of a refrigerant and a lubricant which together form a physical solution, a compressor for discharging refrigerant vapor and entrained liquid working fluid, means for separating the liquid working fluid from the refrigerant vapor discharged by the compressor, means for utilizing the heat generated by the compressor to vaporize off the refrigerant component of the separated liquid, means for utilizing the residuum for lubricating portions of the apparatus, and means for entraining the liquid used as a lubricant in the refrigerant vapor passing 85 to the compressor. 90

13. In a refrigerating apparatus in which a liquid is evaporated in one chamber, the vapor is pumped into another chamber and condensed therein at a higher pressure and thence returned to the first chamber at a reduced pressure, the combination of a compressor for discharging refrigerant vapor and liquid working fluid, a motor for driving the compressor, means for separating the liquid working fluid from the refrigerant vapor discharged by the compressor, means for subjecting the separated liquid to at least a portion of the heat generated by the compressor and the motor for vaporizing off the refrigerant component of the liquid, and means for utilizing the residuum to lubricate portions of the machine. 100

14. In a refrigerating apparatus in which a liquid is evaporated in one chamber, the vapor is pumped into another chamber and condensed therein at a higher pressure and thence returned to the first chamber at a reduced pressure, the combination of a body of liquid working fluid composed of an intimate mixture of a refrigerant and a lubricant which together form a homogeneous mixture or physical solution, a compressor for discharging refrigerant vapor having entrained therein liquid working fluid, a motor for driving the compressor, means associated with the discharge portion of the compressor for separating the entrained liquid working fluid from the refrigerant vapor, means for bringing the separated liquid into heat exchanging relation with the compressor for vaporizing off its refrigerant component, means for utilizing the residuum of the liquid working fluid as a lubricant for the compressor and then for the motor, and means 110

for returning said lubricating fluid to the inlet of the compressor.

15. The method of lubricating a refrigerating machine which consists in employing a liquid working fluid consisting of a refrigerant and a lubricant which together form a homogeneous mixture or physical solution, of subjecting a portion of said liquid to heat to vaporize off its refrigerant component, and 10 of utilizing the residue as a lubricating fluid for parts of the machine.

16. The method of lubricating a refrigerating machine having a compression mechanism which consists in employing a liquid working fluid consisting of a refrigerant and a lubricant which together form a homogeneous mixture or physical solution, of utilizing at least a portion of the heat generated by the compression mechanism to vaporize off the refrigerant component of the liquid working fluid, and of utilizing the residue as a fluid for lubricating parts of the machine.

17. The method of lubricating a refrigerating machine having a compressor and a motor for driving the compressor which consists in employing a liquid working fluid consisting of a refrigerant and a lubricant which together form a homogeneous mixture or physical solution, of utilizing at least a portion of the heat of the motor to vaporize off the refrigerant component of the liquid working fluid, and of utilizing the residue as a fluid for lubricating parts of the machine.

35 18. The method of lubricating a refrigerating machine having a compressor and a motor for driving the compressor which consists in employing a liquid working fluid consisting of a refrigerant and a lubricant which together form a homogeneous mixture or physical solution, of utilizing at least a portion of the heat generated by both the compressor and the motor to vaporize off the refrigerant component of the liquid working fluid, and of utilizing the residue as a fluid for lubricating the working parts of the machine.

19. The combination with a refrigerating apparatus embodying a high-pressure portion including a condenser and a low-pressure portion as well as a compressor for translating refrigerant vapor from the low-pressure portion to the high-pressure portion, of means for entraining liquid working fluid having both refrigerant and lubricant constituents in the refrigerant vapor passing to the compression mechanism, and means for subjecting said entrained liquid working fluid, upon its discharge from the compression mechanism, to heat for vaporizing off the refrigerant constituent of the entrained liquid, whereby the remaining portion of the entrained liquid may be utilized as a lubricant for the refrigerating apparatus.

65 20. The combination with a refrigerating

apparatus embodying a high-pressure portion including a condenser and a low pressure portion as well as a compressor for translating refrigerant vapor from the low-pressure portion to the high-pressure portion, of means for entraining liquid working fluid having both refrigerant and lubricant constituents in the refrigerant vapor passing to the compression mechanism, means for subjecting said entrained liquid working fluid, upon its discharge from the compression mechanism, to at least a portion of the heat generated by the compression mechanism for vaporizing off the refrigerant constituent of the entrained liquid, and means for utilizing the residuum of the liquid thus treated as a lubricating fluid for the refrigerating apparatus.

21. The combination with a refrigerating apparatus embodying a high-pressure portion including a condenser and a low-pressure portion as well as a compressor driven by a motor for translating refrigerant vapor from the low-pressure portion to the high-pressure portion, of means for entraining liquid working fluid having both refrigerant and lubricant constituents in the refrigerant vapor passing to the compressor, means for separating the entrained liquid working fluid from the refrigerant vapor upon its discharge from the compressor, means for subjecting the separated entrained liquid working fluid to at least a portion of the heat generated by the compressor and the motor for vaporizing off the refrigerant constituent of the entrained liquid, and means for utilizing the liquid thus treated as a fluid for lubricating the refrigerating apparatus.

22. The combination with a refrigerating apparatus including a compressor, a motor for driving the compressor and a hermetically sealed casing enclosing the motor and the compressor, of means provided within the casing for retaining a body of liquid having both refrigerant and lubricant constituents, said retaining means being disposed in heat exchanging relation with the compressor, whereby the refrigerant constituent of the body of liquid is vaporized off by the application of at least a portion of the heat generated by the compressor, means for condensing the refrigerant vapor thus formed, and means provided within the casing for conveying the liquid thus treated to the working parts of the compressor and the motor for lubricating the same.

23. The combination with a refrigerating apparatus including a compressor, a motor for driving the compressor and a hermetically sealed casing enclosing the motor and the compressor, of means provided within the casing for retaining a body of liquid having both refrigerant and lubricant constituents, said retaining means being disposed in heat exchanging relation with the motor, whereby

- the refrigerant constituent of the body of liquid is vaporized off by the application thereto of at least a portion of the heat generated by the motor, means for condensing the refrigerant vapor thus produced, and means provided within the casing for conveying the heated liquid to the working parts of the compressor and the motor for lubricating the same.
24. The combination with a refrigerating apparatus including a compressor, a motor for driving the compressor and a hermetically sealed casing enclosing the motor and the compressor, of means provided within the casing for retaining a body of liquid having both refrigerant and lubricant constituents, said retaining means being disposed in heat exchanging relation with the compressor and the motor, whereby the refrigerant constituent of the body of liquid is vaporized off by the application of at least a portion of the heat generated by the compressor and the motor, means for condensing the refrigerant vapor thus liberated, and means provided within the casing for conveying the heated liquid to the working parts of the compressor and the motor for lubricating the same. 25
24. The method of lubricating a refrigerating machine which consists in employing a liquid working fluid consisting of a refrigerant and a lubricant which together form a homogeneous mixture or physical solution, maintaining a portion of said fluid predominantly lubricant by the application of heat, and using said portion to lubricate parts of the machine. 30
24. The method of lubricating a refrigerating machine which consists in employing a liquid working fluid consisting of a refrigerant and a lubricant which together form a homogeneous mixture or physical solution, maintaining a portion of said fluid predominantly lubricant by the application of heat, and using said portion to lubricate parts of the machine. 35

In testimony whereof, I have hereunto subscribed my name this 22nd day of May, 1923.

ANDREW A. KUCHER.
